UNITED STATES PATENT OFFICE.

HARRY BLOUNT, OF OAK PARK, ILLINOIS, ASSIGNOR TO WESTERN ELECTRIC COMPANY, INCORPORATED, OF NEW YORK, N. Y., A CORPORATION OF NEW YORK.

WIRE-DRAWING-DIE GUARD.

Application filed January 28, 1927. Serial No. 164,200.

This invention relates to material working apparatus, and more particularly to improvements in wire drawing apparatus.

The object of this invention is to provide an efficient and reliable device for preventing accidental displacement of dies from a die supporting block of a wire drawing apparatus due to the whipping action developed in the trailing end of the wire.

In accordance with the general features of this invention as applied to a high speed wire drawing apparatus having a horizontally disposed block for supporting a plurality of dies through which the wire to be reduced in diameter is progressively drawn, a pivotal shield-like member is resiliently maintained in operative position with respect to the die block to prevent displacement of the dies carried thereby, due to the whipping action of the trailing end of the wire as it passes through the dies. The die retaining member is arranged for movement to permit accessibility to the dies during the stringing operation and is automatically returned to its operative position when doors which enclose the wire drawing apparatus are moved to a closed position.

Other objects and advantages of this invention will more fully appear from the following detailed description taken in connection with the accompanying drawing illustrating one embodiment thereof, in which—

Fig. 1 is a fragmentary front elevation of a wire drawing apparatus embodying the features of this invention;

Fig. 2 is an enlarged plan view of a die block shown in Fig. 1 with the die retaining member in operative position thereon, the dotted line position thereof being its inoperative position;

Fig. 3 is a fragmentary front view thereof, and

Fig. 4 is an enlarged fragmentary plan view partly in section showing in detail the mechanism for mounting and operating the doors of the apparatus and the cooperation between the doors and the die retaining member for automatically moving the member into its operative position upon closure of the doors.

Referring now to the drawing in detail and particularly to Fig. 1 thereof, a framework 11 for supporting the various elements of a wire drawing apparatus embodying

the features of this invention is shown fragmentarily. A compartment 12 supported by the frame work 11 is provided with an opening 13 in its front wall which is adapted to be closed by cooperating doors 14 shown fragmentarily in Fig. 4, and which will be referred to hereinafter. Rotatably mounted in the compartment 12 is a plurality of integral capstans 17—17 of gradually increasing diameters. The capstans 17 are fixed to a horizontal shaft 18 journaled in bearings (not shown) carried in the compartment 12 and driven by an electrical motor or other suitable source of power (not shown). Disposed above the shaft 18 are a plurality of sheaves or guide rolls 19 which are independently rotatable upon a horizontally mounted shaft 20 supported within the compartment 12. For a detailed illustration and description of the rolls 19, capstans 17 and driving mechanism for the latter, reference may be had to Patent 1,598,937 to John N. Selvig, dated September 7, 1926. The details of these elements have been omitted from the present application for the sake of simplicity, since a full disclosure of the particular construction of the rolls, capstans and driving mechanism is not essential to a complete understanding of this invention.

Mounted within the compartment 12 intermediate the capstans 17 and the rolls 19 is a die block 21 provided with upper and lower horizontal shelves 22, each of which carries a plurality of wire drawing dies 23 (Figs. 2 and 3) of gradually decreasing diameters. A supply (not shown) of wire 24 to be reduced in diameter is mounted near the bottom of the framework 11, the wire being guided from the supply over and under guide pulleys 26 and 27, respectively, and thence over the rear guide roll 19 and through the first reducing die 23, which is the extreme upper die as viewed in Fig. 2, carried by the die block 21. The wire 24 is then wound once around the capstan 17 of smallest diameter, after which it is passed upwardly and over the next roll 19, through the next reducing die and around the next capstan, etc., etc., until it is finally reduced to the correct diameter by the last die. From the latter die the drawn wire 24 is passed around the capstan 17 of largest diameter, after which it is guided by sheaves 30 and 32 to a take-up spool 34, dotted lines 110

(Fig. 1), driven by suitable mechanism mounted in a housing 35. The guide sheave 32 is mounted upon the free end of a pivotal tension arm 36 which forms part of an elastic leverage mechanism 37 provided to control the speed of the take-up spool 34 responsive to the tension on the drawn wire between the take-up spool and last reducing die. For a detailed illustration and description of the mode of operation of the leverage mechanism 37, reference is made to the hereinbefore referred to patent, since this mechanism is identical with that disclosed in this patent.

Pivoted in a vertical plane upon the forward end of the die block 21 as viewed in Figs. 1, 2 and 3 is a shield-like member 40 which extends rearward as viewed in Fig. 2 for such a distance that it lies adjacent a plurality of dies 23 carried upon the forward end of each of the shelves 22. The dies just mentioned are the "high speed dies" or the dies through which the wire is drawn with the greatest speed and consequently the dies most likely to be thrown or displaced from the block 21 upon the trailing end of the wire setting up a whipping action as it passes through the dies. The member 40 is provided with a pair of separated lugs 41 which engage opposite ends of a lug 42 provided upon the block 21, a pin 43 passing through aligned openings in the lugs 41 and 42 serves as a pivot for the member. The member 40 is resiliently maintained in either its closed or operative position as shown in full lines in Figs. 1, 2 and 3, or its open or inoperative position as shown in dotted lines in Figs. 2 and 4 by a coiled tension spring 44 attached at opposite ends to the member 40 and the block 21. The movement of the member 40 about its pivot 43 to either its closed or open position is limited by opposed surfaces 45 and 46, respectively, thereof engaging a vertical surface of the block 21. Formed integral with the member 40 upon the upper end of the vertical wall thereof is a horizontal flange or ledge 47 which extends toward the dies 23 above the upper or entrance sides thereof and over the upper edge of the upper shelf 22.

Referring now to Fig. 4, as previously stated, the front of the compartment 12 is closed by cooperating doors 14. The doors 14 are each secured to a depending arm 50 of a bracket 51. These brackets 51 are each provided with two other arms 52 spaced apart, one above the other, and integral therewith. Only the upper arm 52 is indicated in the drawings, the other being directly therebelow. Mounted between the arms 52 is a bifurcated end of a lever 53, the bifurcated portions thereof carrying adjustable bearing pins 56 which project within bearings carried by the arms 52. The doors 14 are supported on the levers 53 which

are fastened to stub shafts 57 rotatably mounted within suitable bearings carried by the top wall 11 of the compartment 12. One end of each of the shafts 57 has integral therewith a segmental gear 59, which gears mesh with each other. Each of the upper arms 52 is provided with a roller 60 which fits within an arcuate slot 61 formed in a plate member 64 secured to the top wall 11 of the compartment 12. The arcuate slots 61 are each provided with a curved portion 65 to receive the roller 60 when the doors are in the closed position, as shown in Fig. 4. To open the doors 14, either one is moved by means of handles 66 provided thereon, the doors being moved inwardly to the dotted line position thereof as shown in Fig. 4 by its lever 53, which is guided through the medium of the segmental gears 59, which operatively connect the levers 53. It will be observed that when the doors 14 are in their open position they are mounted at opposite sides of the capstans 17 and with the right door between the die supporting block 21 and the inside surface of the right wall 11 of the compartment 12, thus leaving the front of the compartment entirely unobstructed. In this position of the doors 14 the die retaining member 40 may be readily turned by an attendant upon its pivot 42 from its closed to its open position to facilitate the die stringing operation. With the member 40 in its open position, as shown in dotted lines in Figs. 2 and 4, and upon the doors 14 being moved from the extreme right dotted line position to the left dotted line position, it will engage the outer surface of the member 40 and a continued movement of the doors 14 will cause the member to be turned clockwise about its pivot 43. Upon the end of the spring 44 which is attached to the member 40 passing to the left of the pivot, the spring will function to quickly move the member to its operative or closed position, as shown in full lines in Figs. 1, 2 and 3.

During the operation of drawing wire the speed thereof becomes greater as the wire is passed through each succeeding die, due to the gradually increasing diameters of the capstans, so that by the time it reaches the forward dies 23 (Fig. 2) carried upon each of the shelves 22 it is traveling at a very high speed. Upon the free or trailing end of the wire nearing these dies there is developed a whipping action and upon the end of the wire passing through the dies, the reaction to the force exerted upon the dies as the wire is drawn therethrough, taken with the developed whipping action, causes the dies to rise from their supporting shelves and to be thrown or displaced from the block 21 and occasionally lost. A displacement of the dies as just described is prevented by a retaining device embodying the features of

this invention, since upon the dies reacting to the downward force thereon as the wire is drawn therethrough and the whipping action of the fast moving wire, the dies al-
5 though they may rise from the shelves 22 will not be thrown therefrom for they will engage the flange or ledge 47 in the case of the upper shelf and the vertical inside surface of the wall of the member 40 in the
10 case of the lower shelf and thereby deflected back onto their respective supporting shelves.

What is claimed is:

1. In a wire drawing apparatus, a die supporting block a die supported loosely thereon, and a die retaining device comprising means positioned adjacent the block and the die supported thereon for preventing accidental displacement of the die from the block by the action of the wire as it passes through the dies.
2. In a wire drawing apparatus, a die supporting block, a plurality of dies supported loosely thereon, and a die retaining device comprising a member pivotally carried upon the block and normally in position adjacent the dies supported thereon for preventing accidental displacement of the die from the block by the action of the wire as it passes through the dies.
3. In a wire drawing apparatus, a die supporting block, a plurality of dies supported thereon, and a die retaining device comprising means positioned adjacent the block and designed to extend along angularly disposed faces of the dies supported thereon for preventing accidental displacement of the dies from the block by the action of the wire as it passes through the dies.
4. In a wire drawing apparatus, a die supporting block, a plurality of dies supported thereon, and a die retaining device comprising a pivotal member normally positioned adjacent a horizontally disposed edge of the block and provided with a ledge extending toward the dies above the entrance sides thereof for preventing accidental displacement of the dies from the block by the action of the wire as it passes through the dies.
5. In a die supporting device, a die supporting block, a plurality of dies supported thereon, a die retaining device comprising a member pivotally carried upon the block and normally positioned adjacent the block and the dies supported thereon for preventing accidental displacement of the dies from the block upon the trailing end of the wire setting up a whipping action as it passes through the dies, and an elastic medium operatively connected to the member and block for maintaining the member in either its operative or inoperative position.
6. In a wire drawing apparatus, a compartment having an opening in one wall thereof, wire drawing mechanism located

within the compartment including a die supporting block, means normally positioned adjacent the die block and the dies supported thereon for preventing accidental displacement of the dies from the block by the action of the wire as it passes through the dies, and a member for closing the opening in the compartment arranged to effect the automatic return of the means to its normal position upon the operation of the member to its closed position.

7. In a wire drawing apparatus, a compartment having an opening in one wall thereof, wire drawing mechanism located within the compartment including a die supporting block, a member pivotally carried upon the block and normally positioned adjacent the die block and the dies supported thereon for preventing accidental displacement of the dies from the block by the action of the wire as it passes through the dies, and a door for closing the opening in the compartment arranged to effect the automatic return of the member to its normal position upon the operation of the door to its closed position.

8. In a wire drawing apparatus, a compartment having an opening in one wall thereof, wire drawing mechanism located within the compartment including a die supporting block, an element normally positioned adjacent the die block and the dies supported thereon for preventing accidental displacement of the dies from the block upon the trailing end of the wire setting up a whipping action as it passes through the dies, a member for closing the opening in the compartment arranged to effect the automatic return of the element to its normal position upon the operation of the member to its closed position, and means for resiliently maintaining the element in either its normal or inoperative position.

9. In a wire drawing apparatus, a die supporting block, a die supported loosely thereon, and a die retaining device comprising an arcuate shaped member positioned adjacent the block and the die, said device being effective upon an accidental displacement of the die from the block to prevent its further displacement by the action of the wire as it passes through the die.

10. In a wire drawing apparatus, a die supporting block, a die supported loosely thereon, a die retaining device comprising a member pivotally carried upon the block, and resilient means for retaining said member in position adjacent the die supported on the block for preventing accidental displacement of the die from the block by the action of the wire as it passes through the die.

In witness whereof, I hereunto subscribe my name this 11th day of January, A. D. 1927.

HARRY BLOUNT.
